SANITARY GARMENT

Elaine Berg, Minneapolis, Minn.

Application December 23, 1935, Serial No. 55,798

8 Claims. (CL 128—288)

This invention relates to sanitary garments to be worn by women during menstruation periods and the primary object is to provide a textile nether garment in the form of a trunk, with provision for snugly and comfortably retaining the absorbent pad in place, while also providing means for opening the crotch of the trunk, without necessarily lowering the trunk proper, to permit temporary removal of the pad when making urinal or bowel eliminations. The difficulty and objection to other pad supporting devices of the trunk type that have come to my attention is that they cannot properly be worn over foundation garments such as corsets and girdles, and if worn under such garments are extremely inconvenient to manipulate or open for the above noted purposes. To overcome these difficulties I provide a trunk member with an opening extending longitudinally of the crotch, and releasably close this opening with suitable means such as slide fasteners of a conventional type. I further provide a non-metallic means of a novel and efficient character for yieldably securing the pad, thus eliminating the use of safety pins, buckles, or similar mechanical devices. As additional features I provide a novel design and arrangement of rubber or rubberized members, and elastic devices for maintaining the various parts in position in a neat, sanitary, and comfortable manner.

In the accompanying drawing, which illustrates a preferred embodiment of the invention:

Fig. 1 is a front elevation of the garment, with fractional portions broken away.

Fig. 2 is a bottom view of the garment as shown in Fig. 1, with a portion broken away.

Fig. 3 is an enlarged detail plan view, looking down into the garment as on line 3—3 in Fig. 1, the side or leg portions being almost entirely broken away.

Fig. 4 is a front to back sectional elevation on line 4—4 in Fig. 3.

Fig. 5 is an enlarged detail cross section, on line 5—5 in Fig. 4, with the crotch members spread and slightly separated for purpose of better disclosure.

Referring to the drawing more particularly and by reference characters, 5 designates generally a conventional design of trunk garment, and may be made of silk or other suitable light weight material. It is releasably held up on the body by an elastic waist band or other suitable means. The crotch is open lengthwise for a substantial distance, and this opening is normally and releasably secured in closed condition by slide fasteners 6, also of conventional or suitable design,

although snaps, buttons, or other fastening members may be used for this purpose.

The inner or upper surface of the crotch material is faced with two shields, 7, of rubber or rubberized material. These shields lie adjacent to the slide fasteners and one of the shields has a fly extension 8 overlaying the fasteners to protect them from moisture. The shields taper forwardly and rearwardly and are secured, at their outer edges by stitching 9 (Figs. 2 and 5).

A panel 10 is disposed over the shields 7 and is both wider and longer than the latter, so as to project upwardly against the front and rear walls of the trunk, as shown in Figs. 1 and 4, while at its sides projecting downwardly in the leg sections, as shown in Figs. 1 and 5. This panel is secured throughout its end and side edges to the garment proper, by stitching 11. The panel may be made entirely of rubberized material, but I have here shown it in two layers or sheets 12 and 13, the piece 12 being of thin flexible rubber and stitched as at 14 to the somewhat larger silk or fabric facing 13, which attaches to the trunk 5 as at 11.

The panel 10 has an elongated opening 15, 25 running lengthwise of the crotch. The opening 15 is defined by side edges transversely spaced and looped over, as at 16, to form an opening surrounding tube through which extends an elastic cord 17. The ends of this cord may extend 30 through one side of the tube so as to be exposed for tying and length adjustment purposes.

The panel 10 is further provided, upon its upper or inner surface, and adjacent the ends of the opening 15, with front and rear pocket members 35 18 and 19, which open inwardly and downwardly to receive the ends of the absorbent pad 20, which may be of standard or conventional design. The ends of the pad are merely tucked into the pockets and are retained therein by the elasticity of 40 the pocket material which is preferably of rubber. To further assist in the retention of the pad ends, however, or where the pockets are not made of elastic material, I provide the pocket openings 45 with inserted elastic members 21 which will exert the necessary retaining grip over the pad ends.

The parts are so designed and arranged that when the garment is worn the ends of the panel 10 will cooperate with the elastic 17 to stretch 50 longitudinally of the crotch and exert an upward pressure or lift on pad 20 throughout its length and in transversely spaced lines, thus holding the pad properly and comfortably in place. Meanwhile the panel and shield parts are all so ar- 55

ranged as to prevent moisture contact with the fabric parts of the garment.

It is understood that suitable modifications may be made in the structure as disclosed, provided such modifications come within the spirit and scope of the appended claims. Having now therefore fully illustrated and described my invention, what I claim to be new and desire to protect by Letters Patent is:

- 10 1. A garment of the character described comprising a trunk member having a nether crotch portion extending from front to rear, a panel member secured in the trunk over such crotch portion and having a central elongated opening 15 extending lengthwise thereof, means for securing a catamenial pad in the trunk over said panel member, said panel member being elastic in the direction of the crotch so as to yieldably support the pad.
- 20 2. A garment of the character described comprising a trunk member having a nether crotch portion extending from front to rear, a panel member secured in the trunk over such crotch portion and having a central elongated opening 25 extending lengthwise thereof, means for securing a catamenial pad in the trunk over said panel member, said panel member being elastic in the direction of the crotch so as to yieldably support the pad, and a shield device disposed over the crotch portion and under said panel opening.
- 30 3. A garment of the character described comprising a trunk member having a nether crotch portion extending from front to rear, a panel member secured in the trunk over such crotch portion and having a central elongated opening 35 extending lengthwise thereof, means for securing a catamenial pad in the trunk over said panel member, and an elastic member extending about the edge of the panel opening to constrict the same and exert pressure upwardly under the pad.
- 40 4. A garment of the character described comprising a trunk member having a nether crotch portion extending from front to rear, a panel member secured in the trunk over such crotch portion and having a central elongated opening 45 extending lengthwise thereof, means for securing a catamenial pad in the trunk over said panel member, and an adjustable draw member 50 threaded in the panel member about the opening therein to adjust the lifting effect of the panel member on the pad supported thereby.

5. A garment of the character described comprising a trunk member having a crotch opening extending from front to rear, releasable means normally closing the opening, a panel member secured in the trunk over the crotch and having an elongated opening registering with the crotch opening, means for securing the ends of a catamenial pad to the trunk member while disposed over the panel member, said panel member being elastic in the direction of the crotch so as to 10 yieldably support the pad.

6. A garment of the character described comprising a trunk member having a crotch opening extending from front to rear, releasable means normally closing the opening, a panel member 15 secured in the trunk over the crotch and having an elongated opening registering with the crotch opening, means for securing the ends of a catamenial pad to the trunk member while disposed over the panel member, and an elastic member 20 extending about the panel opening to exert pressure upwardly under the pad.

7. A garment of the character described comprising a trunk member having a crotch opening extending from front to rear, releasable means 25 normally closing the opening, a panel member secured in the trunk over the crotch and having an elongated opening registering with the crotch opening, means for securing the ends of a catamenial pad to the trunk member while disposed 30 over the panel member, said panel member being elastic in the direction of the crotch so as to yieldably support the pad, and a pair of shields secured to the trunk member below the panel member and adjacent to the crotch opening.

8. A garment of the character described comprising a trunk member having a crotch opening extending from front to rear, releasable means normally closing the opening, a panel member secured in the trunk over the crotch and having 40 an elongated opening registering with the crotch opening, means for securing the ends of a catamenial pad to the trunk member while disposed over the panel member, said panel member being elastic in the direction of the crotch so as to 45 yieldably support the pad, and a pair of shields secured to the trunk member below the panel member and adjacent to the crotch opening, one of said shields continuing in a fly portion overlying the releasable closing means of the crotch 50 opening.
